UNITED STATES PATENT OFFICE.

EDMOND B. BRONSON, OF BLUE ISLAND, ILLINOIS.

ELECTRIC LANTERN.

Application filed October 23, 1922. Serial No. 596,269.

My present invention relates to improvements in electric lanterns, and has for one of its objects the provision of a lantern composed of separate complete units which, in the event of damage to any of them, will only require the replacement of the unit damaged. For this reason I have designed a battery receptacle and lamp or bulb support and a separable base or stand with means for making an easy and dependable assembly between these parts.

I have also provided the battery receptacle and bulb or lamp support with lateral trunnions for engaging a handle or bail, and have provided means for either permitting the bail to pivot or swing with respect to the battery receptacle; or for securing these parts rigidly in any relation which the trunnions will permit. I have also provided my lantern with a bent wood handle or bail which is light and strong and particularly convenient and desirable for carrying either in the hand or upon the arm.

Another and important object of the invention is the provision of an improved switch mechanism which is preferably installed exteriorly of the battery receptacle and housed in one of the trunnions thereof by which it is protected from accidental injury, and I have arranged this switch so that it may either be manually operated or adjusted so as to be operated by swinging the bail through a certain arc with respect to the battery receptacle.

In connection with the battery receptacle, it will be seen that I have designed the several parts so that they are of a rugged and sturdy character and will withstand a maximum amount of severe service.

Within the cover of the battery receptacle, I have provided a simple clip for receiving and safely holding two additional or spare bulbs.

The electric circuit between the battery, bulb and switch is of copper, insulated where necessary, so that the current is not required or permitted to be grounded or to circulate in the walls of the battery receptacle.

The contact for the lateral battery terminal is spring supported so as to follow and assure contact with the terminal; and is so designed that it will make contact no matter in what angular relation the battery may be inserted into the receptacle.

The conductor between the central termini-

nals of the battery and bulb is made in the form of a helix or coiled spring suitably guided and removably mounted so as to insure contact and electrical connection at all times between the central terminals of the battery and bulb and avoid a breaking of the circuit incident to longitudinal jars of the structure.

All of the foregoing objects I prefer to accomplish in the following manner, reference being made to the accompanying drawings which form a part of this specification, in which

Fig. 1 is an elevation of my improved lantern.

Fig. 2 is a similar view of the structure observed at right angle to Fig. 1.

Fig. 3 is a top plan of the removable support or stand detached from the battery casing and associated parts.

Fig. 4 is a top plan of a fragment of the cover and casing and a transverse section of the handle on line 4-4, Fig. 1.

Fig. 5 is a horizontal section of one of the trunnions, the view being taken on line 5-5, Fig. 1.

Fig. 6 is a central vertical section through the battery casing and associated parts on line 6-6, Fig. 1, and drawn to an enlarged scale.

Fig. 7 is a similar section at a right angle to Fig. 6 and taken on line 7-7, Fig. 2, and also enlarged.

Fig. 8 is a detail plan of the annular contact element in the bottom of the battery casing, the view being taken on line 8-8, Fig. 7.

Fig. 9 is a horizontal section of one of the trunnions and the switch mechanism housed therein, the view being an enlarged horizontal section taken on line 9-9, Fig. 7.

Fig. 10 is a transverse section on line 10-10, Fig. 9 looking in the direction of the arrows.

Observing first Figs. 1, 2 and 3 of the drawings, it will be seen the lantern is provided with a support that comprises a circular band 15 that encircles the lower portion of the casing or body of the lantern, to which band is secured a plurality (preferably four) uprights 16, 16, that incline outwardly and downwardly to a rectangular base 17 to which the lower ends of the uprights are secured by forming loops around the same in the manner shown. The body or casing is a cylindrical shell 18 having a

convex bead 19 in its lower portion against which the upper edge of band 15 engages when the body is inserted into the support above described, and in order to removably lock the body in the support the former may be provided with lateral pins 20 projecting from opposite portions thereof below the bead 19 which pins may engage with ogee or circuituous grooves or channels 21 formed in opposite portions of band 15. One of the pins is carried by a spring 22 (Fig. 6) and is longer than the opposite pin so that when band 15 approaches the bead 19 this longer pin will be projected into a slot 23 formed in one of grooves 21 and thereby latch the parts to prevent their accidental displacement in a manner which will be apparent.

The lower end of shell 18 is closed by a concavo-convex wall 24 having a central tubular portion 25 that is formed into threads upon its outer portion to receive a transparent or translucent globe or shade 26, preferably of glass or other suitable material that is threaded so that it may be screwed upon the exterior of tube 25 to enclose the bulb which is mounted in the manner to be hereinafter described. A suitable reflector 27 of annular shape, and having a threaded edge, is screwed into the interior of the outer end of tube 25, the bulb being positioned in the central aperture of said reflector. The foregoing structure is illustrated in detail in Figs. 6 and 7 of the drawings.

The opposite or upper end of the casing shell 18 is closed by a hinged cover 28 of concavo-convex shape that is maintained in closed position by a spring latch 29 that may be locked against accidental dislodgment by rotating a wing member 30 that co-operates therewith. Upon a convenient portion of cover 28 is or may be placed a luminous disk or button 31 that is secured in position by a ring 32, as shown, so that when the lantern is left unlighted and standing in a dark place it may be readily located by the glow from the disk. The interior of the cover is provided with an elongated spring clip 33 of U-shape in transverse section so that extra bulbs 34 may be stored therein for emergency use, and secured to the interior of the cover by the same element that retains this clip in position is a spring plate 35 the ends of the arms of which are spread apart to engage the upper end of the battery or battery unit 36 that is carried by the housing or casing 18.

Embossments 37 are provided upon opposite sides of casing 18 that are reduced in diameter to provide arbors 38 that are threaded upon their outer ends and are provided with longitudinal slots or grooves 39 to receive the feathers 40 of washers 41 carried upon the smooth portions of the arbors back of the threads. Handle receiving

sockets 42 have their flattened end portions 43 apertured and mounted upon arbors 38 between embossments 37 and washers 41, and the structure is maintained upon the arbors by internally threaded caps 44 that are screwed upon the threaded outer ends of said arbors in the manner shown in Figs. 5 and 9 of the drawings, so that sufficient friction is created between the movable parts in order that the handle will remain in any of the adjusted positions to which it may be moved. The handle 45 is preferably of wood, rattan, bamboo, or the like, that is steamed and bent to a substantially U-shape and has its ends inserted into sockets 42 and retained therein by set-screws 46 threaded transversely into said sockets. It will be seen that by reason of the interposing of feathered washers 41 between the bail and the securing caps upon the trunnions the movement of the bail will not cause, or tend to cause a movement of the outer securing cap.

Mounted in the lower end of casing 18 is a disk 47 of insulating material slightly less in diameter than the interior of casing 18, that is centrally bored to receive a short tube 48, and one edge portion of the disk is cut away or flattened, as at 49 in Figs. 7 and 8 of the drawings, to permit its insertion into or removal from the casing and past the conductor wires where they pass through the casing. Surrounding and extending below the lower end of tube 48 is an electric socket element 50 that is spaced and insulated from the tube by a cylinder of insulating material 51 interposed between the tube and socket elements, and the outer portion of the socket element 50 is provided with oppositely arranged bayonet slots to receive the lateral co-acting studs or pins 53 on the miniature electric light bulb 54 that is mounted in said socket element. Positioned in the tube preferably so that it extends out of the ends thereof is a yieldable, flexible conductor 55 that may be in the form of a helically coiled wire of suitable gage and conductivity, and to the upper and lower ends of which are secured metallic buttons or disks or contact plates 56 and 57, respectively. The lower contact plate 57 bears against the central terminal of bulb 54, and the upper plate 56 is engaged and depressed slightly by the central terminal of the battery or battery unit when the latter is inserted in the casing so that yieldable conductor 55 is compressed and longitudinal jars upon the casing will not tend to cause a breaking of the circuit at these points.

A metallic annulus or concentric element 58 is mounted upon the insulation disk 47 by means of yielding tongues or tangs 59 formed integrally from the metal and are extended downwardly therefrom so as to space and support element 58 out of contact with the insulation disk, except at the loca-

tions of said tongues. One of the tongues is apertured, and a pin 60 passes therethrough and through the insulation disk to secure the concentric element 58 to said disk, and a 5 current conductor 61 leading from the switch (hereinafter described) is connected at one of its ends to said pin and element 58, while a suitable conductor 63 leads from the opposite terminal of said switch to socket 10 element 50. Both of said conductor wires pass through an aperture 64 in the wall of casing 18 at the axis of the adjacent trunnion embossment.

The switch above alluded to comprises a 15 structure that is enclosed within the tubular arbor or sleeve or trunnion 38 of one of the embossments heretofore described, and is illustrated in detail in Figs. 7, 9 and 10 of the drawings. The circular insulating block 65 fits into sleeve 38 and carries posts 66 to which the adjacent ends of conductor wires 61 and 63 are connected. The outer ends of posts 66 are threaded and screwed into small disks or nuts 67 embedded in the outer face 20 of block 65 so as to provide separated or spaced contact elements in the face of the block. Disposed in front of the block is an insulating disk 68 having apertures 69 to receive short stubs 70 on opposite ends of a 25 segmentally shaped switch plate 71 that is preferably of thin metal of suitable conductivity and is preferably bowed transversely intermediately of its ends, as seen in Fig. 9. Centrally of disk 68 is a rectangular aperture to receive the squared end 72 of a stud 30 that is increased in diameter and of circular outline, as at 73, intermediate its ends where it is positioned in a central aperture made in the cap 44. The cap 44 is threaded internally and is screwed upon the threaded outer end of tubular sleeve 38. A rotatable cover 74 fits over cap 46, and, as shown in Fig. 10, has a square aperture in its central portion to receive the correspondingly shaped portion of stud 72. The outer end of stud 72 is cylindrical and threaded, and a nut 75 is screwed thereon to maintain the parts in assembly and to insure the movement or rotation of the switch-carrying disk 45 40 with cover 74. Upon the exterior of cover member 74 is provided a pair of radially projecting lugs 76 that engage the head of a small screw 77 screwed into the laterally inclined portion of plate 43 so that its 50 head may be projected into and out of the path of movement of lugs 76. Bolt 77 may be adjusted so as to remove it from the path of the lugs whenever it is desired.

In order to be able to assemble cap 44 with sleeve 38, I have provided transverse holes 55 58 in the cap and cover 74, which may be brought into registry to receive a pin for holding these two elements against relative movement so that these parts may be screwed upon the threaded end of sleeve 38, and when

this assembly is completed the pin is removed, thereby permitting cover 74 and insulating disk 68 to be rotated, while cap 46 remains in its adjusted position.

When it is desired to open or close the 70 switch, handle 45 is swung in the direction of the arrow in Fig. 2, so that the head of bolt or screw 77 engages the nearest lug 76, and a continued movement of the handle rotates the cover from which the lugs project and operates the connected elements of the switch to close the circuit and light the lamp. This movement of the cover carries the unengaged lug past the center or axis of the stud, or to the left side of the section line 7-7, Fig. 2. When the movement of handle 45 is reversed and moved to the opposite side of the casing, the cover remains stationary until the bolt has engaged the then adjacent or opposite lug 76 so that the 85 further movement of the handle will move the switch parts back to their initial or normal position which causes the switch to break the circuit and extinguishes the bulb.

The battery 36 may be of the mono-cell, 90 multi-cell, or other type that is found desirable or convenient.

What I claim is:

1. In a portable electric lantern a battery receiving casing, trunnions upon opposite 95 sides thereof one of which is hollow, a handle swingingly mounted upon said trunnions, a suitable switch mechanism housed within the hollow trunnion and outside said casing, and means operated by the reciprocation of said handle to open and close said switch.

2. In an electric lantern, a battery casing having a hollow trunnion upon one side, a handle one of the ends thereof being pivotal- 105 ly mounted upon said trunnion and the opposite end is connected to said casing, a block within said trunnion having terminal posts thereon, a segmental shaped switch element frictionally in contact with said block and 110 adapted to be moved into contact with said posts, a rotatable structure for moving said switch element into and out of contact with said posts, and means carried by said handle for engaging said rotatable structure to 115 operate the same.

3. In an electric lantern a battery casing provided with oppositely arranged longitudinally slotted trunnions, a support aperture to receive said trunnions, feathered washers 120 co-operating with said trunnions, and threaded caps operable to secure said support in desired relation with said trunnions.

4. In an electric lantern a battery casing, a hollow longitudinally slotted trunnion, a feathered washer co-operating with said trunnion, a threaded cap co-operable with said trunnion and washer, a cover exterior to said cap, switch elements mounted within said trunnion, and means extending through 130

said cap between an element of said switch and said cover whereby said switch may be operated by a movement of said cover.

5. In an electric lantern a battery casing, a hollow trunnion secured thereto, a stator and a rotor switch element disposed within said trunnion, a closure for the end of said trunnion, and an exterior cap mounted upon the end of said trunnion and secured through 10 said closure to the rotor element of said switch.

6. In an electric lantern a battery casing, a hollow trunnion secured thereto, a stator and a rotor switch element disposed within 15 said trunnion, a closure for the end of said trunnion, an exterior cap mounted upon the end of said trunnion and secured through said cap to the rotor element of said switch, lugs extended from said cap, and a member 20 pivoted upon said trunnion and movable to engage said lugs.

7. In an electric lantern, a stand comprising a base and a body band secured in spaced relation, ogee-shaped diametrically positioned channels in said body band, one whereof is slotted intermediate its ends, a battery casing and lamp support shaped to assemble with the body band of said stand, radial projections thereon adapted to co-operate with said channels and one whereof is 25 depressible to co-operate with said slot.

8. In an electric lantern, a battery casing and lamp support, an annular contact member positioned therein having a plurality of 30 spring tangs produced therefrom to cause said member to yieldingly register with a battery face, and a second contact member comprising a helical spring whereby independent spring actuated contacts are provided for the respective poles of the battery.

9. In an electric lantern, a battery casing and lamp support, a hinged closure therefor

a pair of U-shaped spring clips disposed one within the other and mounted within said closure, one pair thereof provides battery 45 clamps and the other pair provides bulb holding means.

10. In an electric lantern, a battery casing and lamp support, a switch mounted exteriorly of said casing, an insulating disk 50 within said casing, an annular contact carried by said disk and yieldable under pressure of a battery in said casing, a lamp socket mounted upon said disk, conductors extending between said annular contact and 55 lamp socket to the respective terminals of said switch, and an independent spiral conductor extending through said insulating disk and affording electrical connections between a battery pole and a central terminal 60 of an incandescent bulb mounted in said socket.

11. In an electric lantern, a battery casing having a trunnion thereon, a switch assembling cap cooperable with said trunnion, a 65 switch operating member enclosing said cap, switch elements mounted within said trunnion, and means extending through said cap between an element of said switch and said operating member whereby said switch may 70 be operated by movement of said member.

12. In an electric lantern, a battery casing and lamp support, an annular contact member positioned therein having a spring tang produced therefrom to cause said member to 75 yieldingly register with a battery face, and a second contact member comprising a helical spring whereby independent spring-actuated contacts are provided for the respective poles of the battery.

Signed at Chicago, county of Cook and State of Illinois, this 19th day of October, 1922.

EDMOND B. BRONSON.
